(57) CLAIM

The ornamental design for the mounting board of a wall mounted plant holder, as shown and described.

DESCRIPTION

FIG. 1 is a front elevation view of a mounting board of a wall mounted plant holder showing my new design;

FIG. 2 is a left side elevation view, the mirror image being the right side elevation view;

FIG. 3 is a top plan view;

FIG. 4 is a back elevation view; and,

FIG. 5 is a bottom plan view.

The features illustrated in broken lines are shown for illustrative purposes only and form no part of the claimed design.
